INVENTOR.
THOMAS J. LITTLE JR

BY

John Harness

ATTORNEY.

UNITED STATES PATENT OFFICE.

THOMAS J. LITTLE, JR., OF DETROIT, MICHIGAN, ASSIGNOR TO COPELAND PRODUCTS, INC., OF DETROIT, MICHIGAN, A CORPORATION OF MICHIGAN.

REFRIGERATING APPARATUS.

Application filed May 8, 1926. Serial No. 107,568.

My invention relates to improvements in refrigerating apparatus, and more particularly to the heat absorbing unit of the compressor type of refrigerating machine which is generically termed the expansion chamber.

It is the primary object of my invention to provide a heat absorbing unit of a simple and cheap construction.

With these and other objects in view, my invention consists in the arrangement, combination and construction of the various parts of my improved device as described in the specification, claimed in my claims and shown in the accompanying drawings,

15 in which:

Fig. 1 is a plan view of the metal sheet which forms the base of my device.

Fig. 2 is a cross section taken on line 2—2 of Fig. 1.

20 Fig. 3 is a plan view showing the second metal sheet imposed over the surface of the metal sheet which forms the base of my device, and also showing the line of weld by which the two sheets are attached.

25 Fig. 4 is a cross section taken on line 4—4 of Fig. 3.

Fig. 5 is a plan view showing the second sheet imposed over the base sheet and also showing the location of spot welds by which 30 the two sheets are, at various points within their edges, secured together.

Fig. 6 is a cross section taken on line 6—6 of Fig. 5.

Fig. 7 is a plan view showing the means 35 by which pressure is applied to expand the unattached inner surfaces of the sheets forming my device.

Fig. 8 is a cross section taken on line 8—8 of Fig. 7.

40 Fig. 9 is a vertical cross section of a refrigerator cabinet showing my device installed.

In Fig. 1 I have shown a square sheet of metal 1, with circular openings 2 and 3 stamped therein adjacent the edges of two sides of the sheet, said openings 2 and 3 being formed with circular lips 4 and 5 extending outwardly and at right-angles to the surface of the sheet 1 as shown in Fig. 50 2 and said lips 4 and 5 being internally threaded to receive pipes or other threaded fittings.

Metal sheet 6 is then imposed upon that side of sheet 1 which does not carry the extended lips 4 and 5. The edges of said

sheet 6 are then welded to the edges of sheet 1 along the lines 7 as shown in Fig. 3. The inner and adjacent surfaces of sheets 1 and 6 are then secured to each other at spaced intervals by a plurality of spot welds 8 as shown in Fig. 5. A screw plug 9 is then inserted in lip 4, thereby closing opening 2, and a pipe 10 is then inserted in lip 5 and secured therein by fitting 11, thereby closing opening 3 as shown in Figs. 7 and 8. Air, or other like pressure is then applied through pipe 10 to expand and bend away from each other between the spot welds, the unattached inner surfaces of sheets 1 and 6, thereby producing a sufficient space between the inner surfaces of sheets 1 and 6 to permit the circulation of liquid or gas refrigerant between the surfaces of the sheets 1 and 6, and to cause such circulation to be along a devious path. The device 75 formed, as described, by sheets 1 and 6 may then be bent as indicated in Fig. 9, (it being understood, however, that the bending may occur prior to welding and expanding), so that the lips 4 and 5 may be connected with 80 pipes 12 and 13 extended from the heat dissipating mechanism of a refrigerating machine (not shown) through the cabinet 14. The sheets 1 and 6 thus bent and connected with the pipes 13 and 14 as shown in Fig. 9, 85 form a basket-like, or substantially U-shaped container in which may be placed ice trays 15 and 16. This basket-like container so formed and described may be supported in the cabinet 14 by a perforated metal or wire 90 mesh partition 17, which is attached to the inner side walls of cabinet 14 as shown in Fig. 9.

It is evident that the above described heat absorbing mechanism may be much more 95 cheaply and easily constructed than the expansion coils, expansion chambers and brine tanks now in common use, and that it has the additional advantage of providing a container in which may be placed the various 100 articles usually desired to be frozen. The device when in operation has a much quicker freezing action upon articles placed within it, than the expansion coils, expansion chambers and brine tanks now commonly used, 105 because it provides for the articles to be frozen, a greater area of contact with the heat absorbing surface than is provided by the other constructions mentioned, and reduces to a minimum the number of con- 110

ductors through which the heat must pass before being absorbed.

It is obvious that various changes may be made in the arrangement, combination and construction of my improved device without departing from the spirit of my invention, and it is my intention to cover by my claims such changes as may be reasonably included within the scope thereof.

10 What I claim is:

1. In a mechanical refrigerating system, a refrigerant expander unit including two sheet metal plates joined at their peripheral edges and bent to form a container of substantially U-shape, the bottom of said container adapted to serve as a shelf for trays, the sides of said container extending upwardly from the bottom thereof and the

free ends of said sides being bent inwardly towards each other, an inlet for one of said bent ends, and an outlet for the other of said bent ends.

2. An expansion chamber for a refrigerating apparatus comprising a pair of superposed sheet metal plates joined throughout their edges and generally spaced between said edges to form a refrigerant chamber, the ends of said plates being bent upwardly and inwardly into opposed relationship whereby to form a container having a tray 30 receiving recess therein, the bottom of said container adapted to serve as a shelf, a refrigerant inlet for one of said ends, and a refrigerant outlet for the other of said ends.

THOMAS J. LITTLE, JR..
